UNITED STATES PATENT OFFICE.

FRANKLIN B. BREMERMAN, OF INDIANAPOLIS, INDIANA.

INTERNAL-COMBUSTION ENGINE.

1,078,991.

Specification of Letters Patent. Patented Nov. 18, 1913.

Application filed February 7, 1912. Serial No. 676,010.

To all whom it may concern:

Be it known that I, FRANKLIN B. BREMERMAN, a citizen of the United States, residing at Indianapolis, in the county of Marion and State of Indiana, have invented a new and useful Internal-Combustion Engine, of which the following is a specification.

It is the object of my invention to control 10 the inlet and exhaust of engines by means which is positive, accurate and quiet in operation, and which at the same time is comparatively simple and inexpensive in construction.

15 The various novel features of my invention will appear from the description and drawings, and will be particularly pointed out in the claims.

In the drawings, Figure 1 is a partial 20 longitudinal vertical section through a four cylinder internal combustion engine embodying my invention; Fig. 2 is a section on line 2—2 of Fig. 1; and Figs. 3-10, inclusive, are diagrams showing the position 25 of the various parts at different points in the cycle of operation.

The engine illustrated has four cylinders A, B, C, and D. Each cylinder has a main outer cylinder casing 10 provided with a 20 water jacket 14 having the usual water inlet 12 and water exhaust 13. The head 14 of each cylinder is depressed, and is provided at the center with a spark plug 15. Fitting within the casing 10 of each cylinder are two circumferentially reciprocable, concentric sleeves 16 and 17, and fitting within the inner sleeve 17 is a sliding piston 18 connected by a pitman 19 to a common crank shaft 20. The upper ends of the two sleeves 16 and 17 extend into an annular space or chamber 21 between the casing 10 and the depressed head 14, and the upper end of the inner sleeve 17 has a flange 22 extending over the upper end of the sleeve 16. The upper end of the sleeve 16 engages the under side of the flange 22, and the upper end of the sleeve 17 engages the upper end of the chamber 21, on frusto-conical surfaces, so that the 45 joints between such surfaces may readily be ground. To facilitate this grinding, the extreme upper ends of the two sleeves are flattened slightly so that there will be no sharp cutting edges. The sleeves 16 and 50 17 fit closely together near their upper ends, where the parts presently to be described

are located, but to reduce friction may be spaced apart slightly below such ports; and the outer sleeve may be split, if desired, to allow for the expansion due to unequal 60 heating. The inner sleeve 17 is preferably provided with a contracting ring 23 which engages the wall of the chamber 21 formed by the cylindrical surface of the depressed cylinder head 14, and the outer sleeve 16 is 65 provided with two expanding rings 24 bearing against the inner surfaces of the casing 10 above and below the ports referred to. The sleeves 16 and 17 are held in place by upwardly spring-pressed plates 25 carried by 70 cross bars 25' of the engine frame 26 and slidingly bearing against the lower edges 27 of the sleeves 16 and 17, and may be oiled through a pipe 29, preferably supplied 75 from a forced feed oiler.

The ports referred to are the intake and exhaust ports of the engine. Each cylinder casing 10 has an intake port 30 and an exhaust port 31, which coöperate respectively with intake ports 32 and 33 and exhaust 80 ports 34 and 35 in the outer and inner sleeves 16 and 17 respectively. The intake and exhaust ports 30 and 31 are connected by the usual pipes 30' and 31' to the carburetor and muffler, which need no explanation here. 85

By moving the two sleeves 16 and 17 relatively to each other and to the casing, the coöperating ports in such sleeves and casing may be made to register to admit the explosive mixture and discharge the burnt 90 gases at the proper times. To obtain this movement, the crank shaft 20 is provided with a spiral gear 41 which meshes with two spiral gears 42 and 43 mounted on vertical shafts 44 and 45. In a four cycle engine, 95 such as illustrated, the gears 42 and 43 have twice the pitch diameter of the gear 41. At their upper ends the shafts 44 and 45 carry crank arms 46 and 47, one of which, say 46, is 90° behind the other in rotation. The 100 eccentric pins 48 and 49 of these crank arms engage cross slots 50 and 51 in longitudinally reciprocable rods 52 and 53. These reciprocable rods slide backward and forward parallel to the crank shaft 20, and are provided with racks 54 and 55 for each cylinder of the engine. The sleeves 16 and 17 are provided at their lower ends with gear segments 56 and 57 respectively. The gear segments 56 of cylinders A and D and the gear 110 segments 57 of cylinders B and C mesh with the racks 54 of the rod 52, the other gear

segments of the several cylinders meshing with the racks 55 of the rods 53. Thus the outer sleeves 16 of cylinders A and D and the inner sleeves 17 of cylinders B and C are reciprocated circumferentially by the rod 52 in the same manner, and likewise the inner sleeves 17 of cylinders A and D and the outer sleeves 16 of cylinders B and C are reciprocated circumferentially in the same manner by the rod 53. Since the crank arm 47 is 90° ahead of the crank arm 46, the rod 53 completes a movement in either direction at the time the rod 52 is at the center of its movement in such direction. The movements of these two rods are simple harmonic motions, by reason of the manner of their connection with the cranks 47 and 46.

The arrangement of the ports for the various cylinders at different parts in the cycle of operation is evident from Figs. 3 to 10 inclusive. In the position shown in Fig. 3, the piston of cylinder A is at the beginning of its exhaust stroke, that of cylinder B at the beginning of its intake stroke, that of cylinder C at the beginning of its explosion stroke, and that of cylinder D at the beginning of its compression stroke. When the crank shaft 20 has moved 90°, or the shafts 44 and 45 have moved 45°, beyond such position, the parts will be in the position shown in Fig. 4, at which time they will be in the middle of the strokes of which the beginning was shown in Fig. 3. Here the exhaust ports of the cylinder A and the intake ports of cylinder B are fully open, and the rod 53 is in its extreme right hand position. When the crank shaft 20 has again advanced 90° farther, the parts reach the position shown in Fig. 5, thus completing the strokes severally begun in the position shown in Fig. 3 and being ready to commence the respective succeeding strokes. In other words, the piston of cylinder A is now about to begin the intake stroke, that of cylinder B the compression stroke, that of cylinder C the exhaust stroke, and that of cylinder D the explosion stroke. When the crank shaft 20 has again advanced 90° farther, the parts reach the position shown in Fig. 6, or the middle of the strokes respectively begun in the position shown in Fig. 5. Here the exhaust ports of cylinder C and the intake ports of cylinder A are fully open, and the rod 52 is in its extreme right hand position. These strokes are completed when the crank shaft 20 has advanced still another 90°, bringing the parts to the position shown in Fig. 7; at which time, the piston of cylinder A is about to begin the compression stroke, that of cylinder B the explosion stroke, that of cylinder C the intake stroke, and that of cylinder D the exhaust stroke. Another 90° advance of the crank shaft 20 brings these strokes to their middle position, as shown in Fig. 8, where the exhaust ports

of cylinder D and the intake ports of cylinder C are fully open and the rod 53 is in its extreme left hand position; and still another 90° advance of such crank shaft causes the completion of such strokes, bringing the parts to the position shown in Fig. 9. Here the piston of cylinder A is about to begin its explosion stroke, that of cylinder B its exhaust stroke, that of cylinder C its compression stroke, and that of cylinder D its intake stroke. These strokes will be half done when the crank shaft 20 has advanced another 90° to bring the parts to the position shown in Fig. 10, where the exhaust ports of cylinder B and the intake ports of cylinder D are fully open, and the rod 52 is in its extreme left hand position; and will be completed when such crank shaft has advanced another 90° to bring the parts to the position shown in Fig. 3, thus completing the cycle.

The operation of the movable parts being a steady one, without violent jars such as occur in the pop valve type of engine, the operation is practically without noise save from the explosion itself. The operation of the sleeves is positive, so that the intake and exhaust begin and stop accurately at the proper moments.

While I have described my invention as applied to a four cycle internal combustion engine it is not limited to that type of engine, but may be applied, by obvious changes in the relation of the gears and the ports, to other types of internal combustion engines as well as to other than internal combustion engines. The invention is also capable of considerable modification in detail, and I aim to cover all modifications which come within the spirit and scope of my invention as set forth in the following claims.

What I claim as new is:

1. An internal combustion engine having more than two cylinders, a plurality of sleeves concentrically mounted in the casing of each cylinder, said casing and sleeves being provided with intake and exhaust ports, a piston in each cylinder, a common shaft for all the pistons, and two rods harmonically reciprocated from such shaft so that each rod is substantially at one end of its movement when the other rod is at the center of its movement, each of said rods being connected to a sleeve of each cylinder to reciprocate such sleeves circumferentially to open the ports of the cylinders successively.

2. An internal combustion engine having more than two cylinders, a plurality of sleeves concentrically mounted in the casing of each cylinder, said casing and sleeves being provided with intake and exhaust ports, and corresponding ports in corresponding sleeves being of substantially the same size, a piston in each cylinder, a common shaft for all the pistons, and two rods harmonically reciprocated from such shaft

- so that each rod is substantially at one end of its movement when the other rod is at the center of its movement, each of said rods being connected to a sleeve of each cylinder to reciprocate such sleeves to open the ports of the cylinders successively. 70
3. An internal combustion engine having more than two cylinders, each cylinder comprising a casing and two concentric sleeves circumferentially reciprocable in said casing, said casing and sleeves being provided with cooperating ports, and corresponding ports in corresponding sleeves being of substantially the same size, a crank shaft, and 75 a pair of rods reciprocatingly driven harmonically from such crank shaft with twice the period of the latter and so that each rod is substantially at one end of its movement when the other rod is at the center of its movement, each of said rods being connected to one sleeve associated with each cylinder and the rods co-operating with the sleeves to open the ports of the various cylinders successively. 80
4. An internal combustion engine having more than two cylinders, each cylinder comprising a casing and two concentric sleeves reciprocable in said casing, said casing and sleeves being provided with cooperating ports, a crank shaft, and a pair of rods reciprocatingly driven harmonically from such crank shaft with twice the period of the latter and so that each rod is substantially at one end of its movement when the other rod is at the center of its movement, each of said rods being connected to one sleeve associated with each cylinder and the rods co-operating with the sleeves to open the ports of the various cylinders successively. 85
5. An internal combustion engine having more than two cylinders, each cylinder comprising a casing and two concentric sleeves circumferentially reciprocable in said casing, said casing and sleeves being provided with cooperating ports, and corresponding sleeves being of substantially the same size, a crank shaft, and a pair of rods reciprocatingly driven harmonically from such crank shaft so that each rod is substantially at one end of its movement when the other rod is at the center of its movement, each of said rods being connected to one sleeve associated with each cylinder and the rods co-operating with the sleeves to open the ports of the various cylinders successively. 90
6. An internal combustion engine having more than two cylinders, each cylinder comprising a casing and two concentric sleeves reciprocable in said casing, said casing and sleeves being provided with cooperating ports, a crank shaft, and a pair of rods reciprocatingly driven harmonically from such crank shaft so that each rod is substantially at one end of its movement when the other rod is at the center of its movement, each of said rods being connected to one sleeve associated with each cylinder and the rods co-operating with the sleeves to open the ports of the various cylinders successively. 95
7. An engine having more than two cylinders, each cylinder comprising a casing and a sleeve circumferentially reciprocable therein, such sleeves and casings having operating intake and exhaust ports and corresponding ports in the various sleeves being of the same size, a crank shaft connected in common to the pistons of all the cylinders, and a rod reciprocatingly driven harmonically from such crank shaft and connected to a sleeve of each cylinder of the engine to move such sleeves to produce successive opening of the ports of the various cylinders. 100
8. An engine having more than two cylinders, each cylinder comprising a casing and a sleeve reciprocable therein, such sleeves and casings having cooperating intake and exhaust ports and corresponding ports in the various sleeves being of the same size, a crank shaft connected in common to the pistons of all the cylinders, and a rod reciprocatingly driven harmonically from such crank shaft and connected to a sleeve of each cylinder of the engine to move such sleeves to produce successive opening of the ports of the various cylinders. 105
9. A multi-cylinder internal combustion engine, each cylinder comprising a casing, two circumferentially reciprocable concentric sleeves the outer of which fits within such casing and the inner of which fits within the outer, such sleeves and casing being provided with cooperating intake and exhaust ports, and a piston slidably fitting within the inner sleeve, a common crank shaft for all the cylinders, two rods harmonically reciprocated by such crank shaft at half the speed of the latter, and connections between each of said rods and the outer sleeves of less than all the cylinders and the inner sleeves of the remaining cylinders. 110
10. A multi-cylinder internal combustion engine, each cylinder comprising a casing, two reciprocable concentric sleeves the outer of which fits within such casing and the inner of which fits within the outer, such sleeves and casing being provided with cooperating intake and exhaust ports, and a piston slidably fitting within the inner sleeve, a common crank shaft for all the cylinders, two rods reciprocated by such crank shaft at half the speed of the latter, and connections between each of said rods and the outer sleeves of less than all the cylinders and the inner sleeves of the remaining cylinders. 115
11. A multi-cylinder internal combustion engine, each cylinder comprising a casing, two reciprocable concentric sleeves the outer of which fits within such casing and the inner sleeves of the remaining cylinders. 120
12. A multi-cylinder internal combustion engine, each cylinder comprising a casing, two reciprocable concentric sleeves the outer of which fits within such casing and the inner sleeves of the remaining cylinders. 125
13. A multi-cylinder internal combustion engine, each cylinder comprising a casing, two reciprocable concentric sleeves the outer of which fits within such casing and the inner sleeves of the remaining cylinders. 130

- inner of which fits within the outer, such sleeves and casing being provided with co-operating intake and exhaust ports, and a piston slidably fitting within the inner sleeve, a common crank shaft for all the cylinders, two rods harmonically reciprocated by such crank shaft, and connections between each of said rods and the outer sleeves of less than all the cylinders and the inner sleeves of the remaining cylinders. 5
12. A multi-cylinder internal combustion engine, each cylinder comprising a casing, two circumferentially reciprocable concentric sleeves the outer of which fits within such casing and the inner of which fits within the outer, such sleeves and casing being provided with co-operating intake and exhaust ports, and a piston slidably fitting within the inner sleeve, a common crank shaft for all the cylinders, two rods reciprocated by such crank shaft at half the speed of the latter, and connections between each of said rods and the outer sleeves of less than all the cylinders and the inner sleeves 10 of the remaining cylinders. 15
13. A multi-cylinder internal combustion engine, each cylinder comprising a casing, two reciprocable concentric sleeves the outer of which fits within such casing and the inner of which fits within the outer, such sleeves and casing being provided with co-operating intake and exhaust ports, and a piston slidably fitting within the inner sleeve, a common crank shaft for all the cylinders, two rods reciprocated by such crank shaft, and connections between each of said rods and the outer sleeves of less than all the cylinders and the inner sleeves 20 of the remaining cylinders. 25
14. A four cylinder internal combustion engine, each cylinder comprising a casing, two sleeves circumferentially reciprocable in said casing, one of said sleeves fitting within the casing and the other fitting within the first and said casing and sleeves being provided with co-operating intake and exhaust ports, and a piston fitting within the inner sleeve, a crank shaft to which all the pistons are connected, a pair of reciprocable rods driven harmonically from the crank shaft, each of said rods being drivingly connected to the outer sleeves of two of the cylinders and the inner sleeves of the other two. 30
15. A four cylinder internal combustion engine, each cylinder comprising a casing, two sleeves reciprocable in said casing, one of said sleeves fitting within the casing and the other fitting within the first and said casing and sleeves being provided with co-operating intake and exhaust ports, and a piston fitting within the inner sleeve, a crank shaft to which all the pistons are connected, a pair of reciprocable rods driven from the crank shaft, each of said rods being drivingly connected to the outer sleeves of two of the cylinders and the inner sleeves of the other two. 35
16. A four cylinder internal combustion engine, each cylinder comprising a casing, two sleeves reciprocable in said casing, one of said sleeves fitting within the casing and the other fitting within the first and said casing and sleeves being provided with co-operating intake and exhaust ports, and a piston fitting within the inner sleeve, a crank shaft to which all the pistons are connected, a pair of reciprocable rods driven from the crank shaft at half the speed of the latter, each of said rods being drivingly connected to the outer sleeves of two of the cylinders and the inner sleeves of the other two. 40
17. A four cylinder internal combustion engine, each cylinder comprising a casing, two sleeves reciprocable in said casing, one of said sleeves fitting within the casing and the other fitting within the first and said casing and sleeves being provided with co-operating intake and exhaust ports, and a piston fitting within the inner sleeve, a crank shaft to which all the pistons are connected, a pair of reciprocable rods driven from the crank shaft, each of said rods being drivingly connected to the outer sleeves of two of the cylinders and the inner sleeves of the other two. 45
18. A four cylinder internal combustion engine, each cylinder comprising a casing, two sleeves circumferentially reciprocable in said casing, one of said sleeves fitting within the casing and the other fitting within the first and said casing and sleeves being provided with co-operating intake and exhaust ports, and a piston fitting within the inner sleeve, a crank shaft to which all the pistons are connected, a pair of reciprocable rods driven from the crank shaft, each of said rods being drivingly connected to the outer sleeves of two of the cylinders and the inner sleeves of the other two. 50
19. A four cylinder internal combustion engine, each cylinder comprising a casing, two sleeves reciprocable in said casing, one of said sleeves fitting within the casing and the other fitting within the first and said casing and sleeves being provided with co-operating intake and exhaust ports, and a piston fitting within the inner sleeve, a crank shaft to which all the pistons are connected, a pair of reciprocable rods driven from the crank shaft, each of said rods being drivingly connected to the outer sleeves of two of the cylinders and the inner sleeves of the other two. 55
20. An internal combustion engine comprising a cylinder casing having a depressed crank shaft to which all the pistons are 60

- head, forming an annular space between the head and the body of the cylinder casing, a pair of concentric valve sleeves one of which fits around the other and within 5 the cylinder casing, the end of one of said sleeves projecting into said annular space and having an annular flange extending over the end of the other, and the flanged end of such flanged sleeve engaging the end of 10 such annular space, and such flange engaging the end of the other sleeve by frusto-conical surfaces, a piston fitting within the inner sleeve, and means driven from such piston for reciprocating said sleeves circumferentially.
21. An internal combustion engine comprising a cylinder casing having a depressed head, forming an annular space between the head and the body of the cylinder casing, 20 a pair of concentric valve sleeves one of which fits around the other and within the cylinder casing, the end of one of said sleeves projecting into said annular space and having an annular flange extending 25 over the end of the other, and the flanged end of such flanged sleeve engaging the end of such annular space, and such flange engaging the end of the other sleeve by frusto-conical surfaces, a piston fitting within the 30 inner sleeve, and means driven from such piston for reciprocating said sleeves circumferentially, with twice the period of the piston, the reciprocation of one sleeve being out of phase with that of the other.
- 35 22. An internal combustion engine comprising a cylinder casing having a depressed head, forming an annular space between the head and the body of the cylinder casing, a pair of concentric valve sleeves one of 40 which fits around the other and within the cylinder casing, the end of the inner sleeve projecting into said annular space and having an annular flange extending over the end of the other, and the flanged end of such 45 flanged sleeve engaging the end of such annular space, and such flange engaging the end of the other sleeve by frusto-conical surfaces, a piston fitting within the inner sleeve, and means driven from such piston 50 for reciprocating said sleeves circumferentially.
23. An internal combustion engine comprising a cylinder casing having a depressed head, forming an annular space between the head and the body of the cylinder casing, 55 a pair of concentric valve sleeves one of which fits around the other and within the cylinder casing, the end of one of said sleeves projecting into said annular space 60 and having an annular flange extending over the end of the other, and the flanged end of such flanged sleeve engaging the end of such annular space, and such flange
- engaging the end of the other sleeve by frusto-conical surfaces, a piston fitting within the inner sleeve, means driven from such piston for reciprocating said sleeves circumferentially, and means for yieldingly pressing said sleeves into said annular space.
24. An internal combustion engine comprising a cylindrical casing having a depressed head, forming an annular space between the head and the body of the cylinder, a pair of concentric valve sleeves one 75 of which fits around the other and within the cylindrical casing, said two sleeves projecting into said annular space and fitting together and within said annular space by frusto-conical surfaces, said casing and 80 sleeves being provided with cooperating ports, a piston reciprocable within the inner sleeve, and means driven from such piston for reciprocating said sleeves circumferentially.
25. An internal combustion engine comprising a cylindrical casing having a depressed head, forming an annular space between the head and the body of the cylinder, a pair of concentric valve sleeves one 85 of which fits around the other within the cylindrical casing, said two sleeves projecting into said annular space and fitting together and within said annular space by frusto-conical surfaces, said casing and 90 sleeves being provided with cooperating ports, a piston reciprocable within the inner sleeve, and means driven from such piston for reciprocating said sleeves circumferentially, the reciprocation of one sleeve 95 being out of phase with that of the other.
26. An internal combustion engine comprising a cylindrical casing having a depressed head, forming an annular space between the head and the body of the cylinder, a pair of concentric valve sleeves one 100 of which fits around the other and within the cylindrical casing, said two sleeves projecting into said annular space and fitting together and within said annular space by frusto-conical surfaces, said casing and 105 sleeves being provided with cooperating ports, a piston reciprocable within the inner sleeve, means driven from such piston for reciprocating said sleeves circumferentially, and means for yieldingly pressing said sleeves into said annular space.
- In witness whereof, I have hereunto set my hand and seal at Indianapolis, Indiana, this 5th day of February, A. D. one thousand nine hundred and twelve.
- FRANKLIN E. BREHMERMAN. [S. S.]
- Witness:
- FRANK A. VAILE,
G. B. SHAYLEY.
